PRESSURE ROLLER FOR FILM HANDLING APPARATUS

Hermann Freese, Berlin-Reinickendorf, Germany,
assignor to Klangfilm G. m. b. H., Berlin, Germany, a corporation of Germany

Application August 6, 1935, Serial No. 34,877
In Germany February 10, 1934

1 Claim. (Cl. 74—240)

This invention relates to film handling apparatus such as sound motion picture recorders or reproducers, and has for its principal object the provision of an improved means for controlling 5 the operation of a pressure roller which functions to maintain the film in contact with the sprocket wheel.

In apparatus for the recording, reproduction or printing of films, guide or presser rolls adapted to be lifted away on hinges or pivots are known in the art. Such rollers are provided for the purpose of preventing the film strip from jumping out of the teeth of the sprocket wheel, and they are pressed against a stop subject to 10 spring pressure. When hinged away, the swivel lever of this roll also bears on a stop subject to the pressure exerted by a spring. The presser rolls under operating condition press the film strip, for instance, against a stationary glide path or a revolving toothless roller, and when hinged away they also come to be supported 15 yieldingly against a stop.

The invention is concerned with an arrangement of the springs associated with rollers of the said sort, the outstanding feature of the disclosure being that the pivots of the hinged rollers are relieved of all spring pressure.

The invention will be better understood from the following description when considered in connection with the accompanying drawing and its scope will be pointed out in the appended claim.

Referring to the drawing,

Fig. 1 illustrates different positions of the pressure roller, and

Figs. 2 and 3 illustrate various details of its support.

Before going into details of an exemplified embodiment of this invention, the arrangement of the guide rollers as known in the prior art shall again be briefly explained by reference to Fig. 1. 10 denotes the film strip, 11 is a sprocket wheel. The guide roll 12 when in its working position bears against stop or rest 13, while when hinged off as indicated by the broken lines

it comes to bear against the stop 14. In both of these limiting positions, spring forces come to act upon the oscillable lever whereby the necessary pressure against the stops is set up.

An exemplified embodiment according to the invention of a spring arrangement in the rocker point or fulcrum 16 of the rocker lever 15 is illustrated in Fig. 2. As shown in the drawing, two holes 17 and 18 are formed in the fulcrum or pivot 16, while two other holes are formed at 10 19 and 20 in the rocker lever 15. Engaged in the two holes 17 and 19 and in holes 18 and 20 are the beginnings and the ends of two springs 21, 22; the ends of these are substantially parallel, and parallel substantially to the median line 16 of the rocker fulcrum 16. These springs are shown separately in elevation in Fig. 3. The forces which are brought to act, for example, by the spring 21 upon the rocker fulcrum or pivot 16 and the rocker lever 15 comprise a radial and 20 a tangential component. The latter component furnishes the requisite bearing pressure against the stops 13 and 14, while the radial component, in the case mentioned, is neutralized by the oppositely directed radial component of the spring 25 22. When the rocker 15 is turned, the spring 22 comes to occupy the position 22' indicated by the broken lines, with the result that the tangential component is caused to reverse its direction so that the requisite bearing pressures against the 30 stops 13 and 14 are produced.

I claim:

In combination, a sprocket, a pressure roller adapted to cooperate therewith, an arm movably supporting said pressure roller, a pivot for said arm and a spiral spring normally compressed in a non-radial direction between said pivot and said arm for maintaining said roller either in co-operative relation with said sprocket or away therefrom, the said spring having straight extensions at its ends extending into holes in said pivot and said arm parallel with the axis of rotation.

HERMANN FREESE.
